Primary Examiner — Paula Greene(74) *Attorney, Agent, or Firm* — Jackson IPG PLLC; Demian K. Jackson(57) **CLAIM**

The ornamental design for a handle, as shown and described.

DESCRIPTION

FIG. 1 is a perspective view of a handle showing our new design;

FIG. 2 is a front elevational view thereof;

FIG. 3 is a top plan view thereof;

FIG. 4 is a right side elevational view thereof;

FIG. 5 is a left side elevational view thereof;

FIG. 6 is a rear elevational view thereof; and,

FIG. 7 is a bottom plan view thereof.

The broken line showing of the handle portion is included for the purpose of illustrating only and forms no part of the claimed design.
